DESIGN FOR A COAMING BAR

Thomas R. Lilly, Roxbury, Conn.

Application September 18, 1944, Serial No. 115,357

Term of patent 14 years

(Cl. D13—6)

To all whom it may concern:

Be it known that I, Thomas R. Lilly, a citizen of the United States, residing at Roxbury, in the county of Litchfield and State of Connecticut, have invented a new, original, and ornamental Design for Coaming Bars, of which the following is a specification, reference being had to the accompanying drawing, forming part thereof.

torted view on account of the mitered ends, of a coaming bar, showing my new design.

Fig. 2 is a top plan view, and

Fig. 3 is an end view of Fig. 1, showing it from the left end.

I claim:

The ornamental design for a coaming bar, as shown.

THOMAS R. LILLY.
